UNITED STATES PATENT OFFICE

FRANK E. SMITH, OF SCOTTDALE, PENNSYLVANIA

RETURN ROLLER SUPPORT

Application filed June 24, 1929. Serial No. 373,443.

This invention relates to a roller support and, while not limited thereto, relates more particularly to a return roller support for belt conveyers, and has for its object the provision of a novel roller support by which the roller can be lowered while in service an amount sufficient to remove it from contact with the belt, so as to facilitate repairs or removal of the roller while the belt is in operation.

In the drawings:

Figure 1 is a side elevation of a portion of conveyer structure having the return roller of this invention applied thereto.

Figure 2 is a fragmentary sectional plan showing the roller mounting.

Figure 3 is a fragmentary sectional elevation showing the mounting of the roller supporting arm extensions.

Figure 4 is a transverse sectional elevation through the conveyer structure showing the completely assembled return roller mechanism.

Referring more particularly to the drawings, the numeral 2 designates the transversely spaced side channel members of the conveyer frame or support which are adapted to support load carrying rollers (not shown) on their top flanges and to have return rollers depending therefrom.

In carrying out the present invention a hanger member 3 is secured to each of the side channels 2 for a limited movement longitudinally thereof. The hanger members 3 are composed of two parts 4 and 5, the part 4 being shaped to fit over the lower flange of the side channel and the other part 5 extending along the back of said channel. The parts 4 and 5 are connected together by a bolt 6 and a pivot bolt 7 and are secured to the channels 2 by a bolt 8 which extends through elongated slots 9 in the parts 4 and 5 and through an aperture in the web of the channel.

Arm members 10 are pivotally mounted on each of the pivot bolts 7 and have their lower ends apertured to form bearings for a transversely extending shaft 12 which is journaled therein.

A second pair of arms 14 are pivotally con-

nected at their upper ends to the channel members 2 at a point forward of the hangers 3 by a bolt 14^a and depend therefrom. A pair of crank-arms 15 are mounted on and keyed to the shaft 12 and have their ends 55 pivotally connected to the lower ends of the arms 14 as at 15^a.

The arms 10 are provided with extension members 16 at their lower ends for supporting the rollers. The extensions 16 have jaw portions 16^a at their rear end which fit over the lower end of the arm. The jaw portions 16^a and the arm are apertured to receive a vertical pivot bolt 17 which permits transverse swinging movement of the extensions 65 relative to the arms 10. The lower jaw 16^a extends rearwardly under a lug 18 on the arm 10 and the lug 18 and lower jaw 16^a are apertured to receive a locking bolt 19 which serves to prevent swinging movement of the 70 extension until removed.

In the construction shown suitable bearing members 20 are mounted on the extension members 16 and the return roller 21 is journaled therein. It will be understood, however, that if desired the return roller shaft may be fixedly mounted in the extensions 65 and the roller body may carry suitable bearings and be journaled on the shaft, or any other suitable roller construction may be used. 80

The crank-arms 15 have their sleeve portions, through which the shaft 12 extends, squared to receive a suitable crank or other tool by which the shaft 12 and crank-arms 15 may be rotated.

In operation, assuming that the crank-arms 15 are in their lowermost or normal position, and it is desired to lower the return roller 21, the shaft 12 will be rotated counter-clockwise so as to swing the crank-arms 15 upwardly, thus lengthening the distance between the shaft 12 and the upper end of the arms 14 twice the length of the crank-arms 15 and lowering the roller 21 out of contact with the conveyer belt.

If it is now desired to remove the roller 21 for repairs or replacement, it is only necessary to remove the locking bolt 19 from one of the extensions 16 and swing said extension outwardly about the pivot 17, thereby moving 100

said extension away from that end of the roller and freeing that end of the roller and its bearing. The roller may then be moved endwise to free the other end from the extension 16.

6 While I have shown and described one specific embodiment of my invention it will be understood that I do not wish to be limited thereto, since various modifications may be 10 made without departing from the scope of my invention, as defined in the appended claims.

I claim:

1. A vertically adjustable roller mounting comprising in combination a fixed support, 15 a pair of transversely spaced arms pivotally connected at one end to and depending from said support, a shaft journaled in said arms, a second pair of transversely spaced arms pivotally connected at one end to and depending from said support, said second pair of arms being spaced relative to said first pair of arms in a direction parallel with the longitudinal axis of said fixed support, a pair of crank-arms fixedly mounted on said shaft and 20 pivotally connected to the lower free ends of said second pair of arms, an extension pivotally connected to the lower end of each of said first pair of arms for horizontal movement relative thereto, and a roller carried by said extension members, said crank-arms being normally maintained in their downward position and being adapted to be moved to upward position by rotation of said shaft 25 to thereby lower said roller a distance equal to twice the length of said crank-arms.

2. A vertically adjustable roller mounting comprising in combination a fixed support, a 30 pair of transversely spaced hanger members adjustably mounted on said support for limited movement longitudinally thereof, a pair of arms pivotally connected at one end to and depending from said hanger members, a shaft journaled in said arms, a second pair of transversely spaced arms pivotally connected at one end to and depending from said support, said second pair of arms being spaced relative to said first pair of arms in 35 a direction parallel with the longitudinal axis of said fixed support, a pair of crank-arms fixedly mounted on said shaft and pivotally connected to the lower free ends of said second pair of arms, and a roller carried by 40 said first pair of arms.

3. A vertically adjustable roller mounting comprising in combination a fixed support, a pair of transversely spaced arms pivotally connected at one end to and depending from 45 said support, a shaft journaled in said arms, a second pair of transversely spaced arms pivotally connected at one end to and depending from said support, said second pair of arms being spaced relative to said first pair of arms in a direction parallel with the longitudinal axis of said fixed support, a pair of crank-arms fixedly mounted on said shaft and pivotally connected to the lower free ends of said second pair of arms, an extension pivotally connected to the lower end of each of said first pair of arms for horizontal movement relative thereto, and a roller carried by 50 said extension members.

4. A vertically adjustable roller mounting 55 comprising in combination a fixed support,

a pair of transversely spaced hanger members adjustably mounted on said support for limited movement longitudinally thereof, a pair of arms pivotally connected at their upper ends to and depending from said hanger members and movable in a direction longitudinally of said support, a shaft journaled in said arms, a second pair of transversely spaced arms pivotally connected at their upper ends to and depending from said support 70 and movable in a direction longitudinally of said support, said second pair of arms being spaced relative to said first pair of arms in a direction parallel with the longitudinal axis of said fixed support, a pair of crank-arms fixedly mounted on said shaft and pivotally connected to the lower free ends of said second pair of arms, an extension pivotally connected to the lower end of each of said first pair of arms for horizontal movement relative thereto, and a roller carried by said extension members, said crank-arms being normally maintained in their downward position and being adapted to be moved to upward position by rotation of said shaft 75 to thereby lower said roller a distance equal to twice the length of said crank-arms.

5. A vertically adjustable roller mounting comprising in combination a fixed support, a pair of transversely spaced arms pivotally connected at one end to and depending from said support, a shaft journaled in said arms, a second pair of transversely spaced arms pivotally connected at one end to and depending from said support, said second pair of arms being spaced relative to said first pair of arms in a direction parallel with the longitudinal axis of said fixed support, a pair of crank-arms fixedly mounted on said shaft and pivotally connected to the lower free ends of said second pair of arms, an extension pivotally connected to the lower end of each of said first pair of arms for horizontal movement relative thereto, means for locking said extensions against movement, and a roller carried by said extension members. 100

In testimony whereof, I have hereunto set my hand.

FRANK E. SMITH. 115
